UNITED STATES PATENT OFFICE.

CLEMENT L. SHOCKLEY AND HARVILA EBER STRALEY, OF SPRINGFIELD, OHIO.

STARTING MECHANISM FOR INTERNAL-COMBUSTION ENGINES.

1,102,091.

Specification of Letters Patent. Patented June 30, 1914.

Application filed July 24, 1912. Serial No. 711,282.

To all whom it may concern:

Be it known that we, CLEMENT L. SHOCKLEY and HARVILA EBER STRALEY, citizens of the United States, residing at Springfield, in the county of Clark and State of Ohio, have invented new and useful Improvements in Starting Mechanism for Internal-Combustion Engines, of which the following is a specification.

10 This invention relates to means of the nature of an attachment which may be fitted to an engine of the internal combustion type for starting the same without requiring the usual manual cranking, which is objectionable because of the danger incident thereto and the inconvenience and annoyance resulting therefrom.

20 The invention contemplates means for positively charging the cylinders of a multiple engine with a gaseous mixture so that when throwing the switch the charge in the cylinder having the piston farthest advanced will be ignited, thereby overcoming inertia of the parts and starting the engine.

25 The invention provides means which admit of training the terminals of the spark plugs as well as supplying a decarbonizing agent to the cylinders for loosening and removing soot and like carbon residue.

30 The invention furthermore has for its object the provision of a novel form of spark plug in which the terminals of the electrodes are immersed in gasoline or other liquid fuel constituting the volatile hydrocarbon from which the gaseous mixture is produced.

35 The invention consists of the novel features, details of construction and combination of parts, which hereinafter will be more particularly set forth, illustrated in the accompanying drawings, and pointed out in the appended claims.

40 Referring to the drawings, forming a part of the specification, Figure 1 is a detail view, showing the application of the starting mechanism to a multiple engine adapted for driving an automobile. Fig. 2 is a sectional view of the tank containing the pumps, the liquid fuel and the decarbonizer. Fig. 3 is a sectional view of one of the spark 45 plugs.

50 Corresponding and like parts are referred to in the following description, and indicated in all the views of the drawings, by the same reference characters.

55 The attachment comprises a tank 1, feed pipes 2 leading therefrom to the cylinders

of the engine and actuating means for the pump mechanism, the same comprising a flexible shaft 3 and a hand wheel 4. This attachment may be applied to any make or variety of internal combustion engine utilizing an ignition system of the electric type. In order to adapt the attachment for various types of explosive engines spark plugs of special design have been devised, said spark 60 plugs being fitted to the cylinders of the engine in the ordinary way and adapted to have the feed pipes connected thereto, whereby the gaseous mixture or other agent may be supplied to the cylinders of the engine as required. The tank 1 may be conveniently located as also the hand wheel 4. When the starting mechanism is fitted to an automobile the tank 1 is preferably attached to the dash 5 and the hand wheel 4 is secured 70 to the steering post 6 within convenient reach of the hand wheel and control levers. 75

The tank 1 is of a size to contain a small quantity of liquid fuel, such as gasoline, and receives the pumping mechanism and 80 the reservoir for containing the decarbonizing agent. The tank is closed by means of a cover which is removable and has the internal mechanism attached thereto so as to be removed with the cover. A manifold 7 is 85 arranged within the lower portion of the tank 1 and the several feed pipes 2 connect therewith. Pump cylinders 8 are arranged within the tank and have connection with the manifold 7, a valve 9 being arranged 90 within each connection so as to prevent back flow into the pump cylinders or barrels. A plunger 10 is arranged to reciprocate in each pump barrel, each plunger having a head 11 with which an eccentric 12 cooperates to effect a reciprocating movement of the plunger. The eccentrics 12 are secured to a shaft 13 and have a progressive arrangement so as to charge the cylinders of the engine in rotation. The flexible shaft 3 100 is made fast to the shaft 13. A valve 14 is located in the length of the manifold 7 so as to shut off communication between the feed pipes and the inlets of the decarbonizing agent and gaseous mixture. A rod 15 connected with the valve 14 extends through the cover of the tank and is provided with a button or knob for convenience of operating the valve. An air pipe 16 depends from the cover of the tank and extends within a 105 short distance of the bottom thereof and has a plurality of small openings 17 in its

110

lower portion for the discharge of air into the gasoline or liquid fuel in a number of small jets. A second pipe 18 is connected with the cover of the tank and is attached at its lower end to the manifold 7. A plurality of openings 19 are had in the sides of the pipe 18 above the level of the gasoline or liquid fuel of the tank. A second set of openings 20 are formed in the lower portion 10 of the pipe 18. A hollow stem 21 is located within the pipe 18 and extends through the cover of the tank and has screwthread connection with the pipe 18. The projecting end of the stem 21 has a button or finger piece to be grasped when it is required to turn the stem to effect a longitudinal movement thereof. The lower end of the hollow stem 21 is made tapering, as indicated at 22, and constitutes a valve for closing the lower 15 end of the pipe 18, thereby preventing the liquid fuel from passing into the manifold. When the valve 22 is seated the gaseous mixture may be drawn from the upper portion of the tank 1 into the pumps and forced 20 therefrom into the cylinders of the engine 25 preliminary to starting.

A receptacle 23 is located within the tank 1 and is adapted to contain a quantity of decarbonizing liquid. The lower portion of 30 the receptacle 23 is connected with the manifold 7. A valve 24 is adapted to close the discharge opening of the receptacle, said valve having its stem extending above the tank and provided with a button or 35 finger piece. When the valve 25 is open the decarbonizing liquid may be forced into the cylinders of the engine by operating the pumps through the hand wheel 4. The spark plug designed as a part of the starting 40 mechanism comprises a shell 25 which is externally threaded to make screwthread connection with the engine in the usual way. The bottom of the shell consists of a cup 26 which is adapted to hold a small quantity 45 of gasoline or other liquid fuel. The centrally disposed electrode is indicated at 27 and its sparking terminal extends into the cup 26 so as to be immersed in the gasoline or other liquid fuel contained therein. A 50 passage 28 is formed in the shell 25 and is arranged to deliver the gasoline into the cup 26. One of the feed pipes 2 connects with the passage 28 of each of the spark plugs.

55 When it is required to start the engine provided with mechanism embodying the invention the valve 14 is opened and the hand wheel 4 is operated, thereby rotating the shaft 13 and operating the series of 60 pumps, each forcing a like quantity of gaseous mixture into a cylinder of the engine. It being remembered that the pumps are of like capacity and each forces a like quantity of gaseous mixture into a cylinder 65 of the engine, the mixture thus forced into

the cylinder having the piston farthest advanced therein will be subjected to the greatest pressure, hence upon throwing the switch to close the circuit explosion will take place in the cylinder of the engine having the 70 piston farthest advanced, thereby starting the engine. After the engine has started the valve 14 is closed. When the pumps are in operation within the tank 1 air is drawn into the pipe 16 and is discharged therefrom 75 through the opening 17 into the gasoline or liquid fuel and passes upward through such fuel into the space in the upper portion of the tank. The gaseous mixture is drawn from the upper portion of the tank through 80 the pipe 18 into the manifold and from thence into the pump barrels from which it is discharged into the engine cylinders by means of the feed pipes 2. Gasoline or liquid fuel may be supplied to the engine cylinders by opening the valve 22, thereby permitting the gasoline to pass from the tank through the opening 20 into the pipe 18, thence to the cylinders of the engine through 85 the manifold and feed pipes. If it be required to supply the decarbonizing liquid 90 to the cylinders the valve 22 is closed and the valve 24 opened so that the decarbonizer may be drawn from the receptacle 23 and discharged into the cylinders of the engine 95 so as to loosen and remove the soot or other residue resulting from combustion. The mechanism is such as to be readily applied to any make of internal combustion engine without requiring any special alteration or 100 change in the parts thereof other than to replace the ordinary spark plug by means of the spark plug herein described.

When the engine is cold and requires a rich mixture to start readily a small quantity of gasoline is supplied to the cup 26 105 and is gasified by the mixture entering the cylinder through the passage 28 when the starting mechanism is brought into play. This operation also serves to keep the spark 110 terminals free from soot and carbon.

From the foregoing description, taken in connection with the accompanying drawings, the advantages of the construction and of the method of operation will be readily apparent to those skilled in the art to which the invention appertains, and while we have described the principle of operation of the invention, together with the device which we now consider to be the best embodiment 115 thereof, we desire to have it understood that the device shown is merely illustrative, and that such changes may be made when desired as are within the scope of the claims appended hereto.

125 Having thus described the invention what is claimed as new, is:—

1. In engine starting mechanism of the character described, the combination of a tank having a liquid fuel space in its lower 130

portion and a gaseous mixture space in its upper portion, a pipe for supplying air into the lower portion of the fuel space, a second pipe having connection with both 5 the liquid fuel and gaseous mixture space, a valve for closing the lower end of the second pipe, a pump for drawing air into the tank and adapted to draw either the gaseous mixture or the liquid fuel there- 10 from through the before mentioned second pipe, and means for delivering such fuel into the cylinder of the engine.

2. In an engine starting mechanism, the combination of a tank having a space in its 15 upper portion and adapted to have its lower portion supplied with liquid fuel, a manifold at the lower portion of the tank, a plurality of pumps one for each cylinder of the engine having connection with the manifold and adapted to be operated to supply the cylinders of the engine in rotation, feed pipes connecting the pumps with the cylinders of the engine, a pipe arranged to supply air to the liquid fuel space of the tank, a second pipe having communication with both the upper and the lower portions of the 20

tank and with the said manifold, and a valve for closing the lower end of the said second pipe.

3. In engine starting mechanism, the combination of a tank having air and fuel spaces, a manifold, a plurality of pumps one for each cylinder of the engine having connection with the manifold, feed pipes connecting the pumps with the cylinders of the 30 engine, means for supplying air to the fuel space of the tank, a pipe having connection with the manifold and in communication with the air and fuel spaces of the tank, a valve for closing the lower end of said pipe, 35 a receptacle containing a liquid decarbonizing agent connected with the said manifold, and a valve for controlling the discharge of the decarbonizer from the said receptacle. 40

In testimony whereof we affix our signatures in presence of two witnesses.
